SKATING SHOE AND THE LIKE

Charles Jewtraw, New York, N. Y.

Application February 26, 1941, Serial No. 380,615

2 Claims. (Cl. 36—71)

This invention relates to new and useful improvements in skating or other athletic shoes.

More specifically the invention proposes the construction of a skating shoe characterized by a shoe having an ice skate attached thereto and provided on the inside thereof with pads of rubber or cotton covered rubber at certain points in a manner to protect one's foot.

Still further the invention proposes the location of one pad on either side of the vamp of the shoe and extending along one's big and little toe for the purpose of preventing the formation of corns and bunions.

Still further the invention proposes the location of inserts of rubber along the sides of the shoe on either side of the laced area for engaging the instep of one's foot to protect this area against being bruised by the engagement of the lace and eyelets thereagainst and to afford more freedom in bending when the shoe is laced.

Still further the invention proposes a means for removably and adjustably mounting the inserts which engage one's instep in a manner to permit the position of these pads to be shifted to a more desirable position so as to properly protect the instep and afford freedom in bending.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a skate shoe constructed in accordance with this invention.

Fig. 2 is an enlarged vertical sectional view taken on the line 2—2 of Fig. 1.

Fig. 3 is an enlarged vertical sectional view taken on the line 3—3 of Fig. 1.

Fig. 4 is a side elevational view of a skate shoe constructed in accordance with a modification of this invention.

Fig. 5 is an enlarged sectional view taken on the line 5—5 of Fig. 4.

Fig. 6 is a plan view of the instep pad used in connection with the form of the invention shown in Fig. 4.

Fig. 7 is a side elevational view of a figure skate constructed in accordance with a modification of this invention.

Fig. 8 is a perspective view of the shoe shown in Fig. 7 with the lace completely removed and the shoe open.

Fig. 9 is a sectional view on the line 9—9 of Fig. 7.

Fig. 10 is a side elevational view of a ski boot constructed in accordance with this invention.

5 The skating shoe according to this invention is characterized by a shoe 10 constructed of leather or other similar material and provided with an open side adapted to be closed by means of a lace 11. A tongue 12 is projected upwards 10 in back of the lace 11 for closing the space between the material of the shoe on either side of the opening. The lace 11 is engaged through eyelets 13 mounted on either side of the opening of the shoe. The shoe 10 carries a conventionally constructed ice skate 14 which is attached to a metal plate 15 which in turn is attached to the sole 16 of the shoe 10. It will be noted that this invention is shown applied to a shoe carrying an ice skate, however, it is not believed desirable to limit this invention to an ice skating shoe as it might be well applied to a shoe carrying a roller skate or an athletic shoe of the type worn in games such as football, basketball, and ski boots, bowling shoes or other 20 similar shoes.

It is proposed to mount pads of cotton covered rubber at specific points on the inside of the shoe 10 for the purpose of protecting certain areas of one's foot. A pad having a core of rubber 17 is 30 enclosed within a cotton casing 18 and is positioned on the inside of the shoe at a point adjacent the joint of one's big toe for preventing the formation of a bunion. This pad is held in position by means of stitches engaged through the shoe upper and through the cloth casing 18 which encloses the core 17. A similar pad having a core of rubber 20 engaged within a cotton casing 21 is positioned within the upper at a point to extend along one's little toe to prevent 40 the formation of corns. This pad is also held in position by means of stitches 22 engaged through the shoe upper and through the cotton casing 21.

Instep inserts are also provided for extending 45 along the top of one's instep to prevent the lace 11 and eyelets 13 from coming in direct contact with one's instep and allow freedom in bending. There are two of these instep inserts one on either side of the open face of the shoe. 50 Each pad is characterized by a core of rubber 23 enclosed within a cotton casing 24. These instep inserts are held in position by means of stitches 25 extending through the shoe upper and through the cloth casing 24. Instep pads 55 are particularly useful in that they prevent the

formation of blisters and bruised areas upon one's instep particularly upon the instep of persons accustomed to wearing low cut shoes and afford freedom in bending when the shoe is tightly laced.

The manner in which this shoe is used is as follows:

The purchaser of a pair of ice skates or other similar athletic equipment receives the shoe 10 in the condition shown in Fig. 1 with the pads of rubber secured in position therein at the designated areas. When the shoe is engaged upon one's foot the pads will take the desired positions for protecting the desired points of one's foot in view of the fact that they are fixedly maintained in position within the shoe upper. An engagement of the rubber pads against the big and little toes and the inserts along the instep of one's foot will protect these areas from being bruised and so add to the enjoyment derived from using the shoe constructed in this manner.

According to the modification of the invention disclosed in Figs. 4 to 6 the construction of the skating shoe is similar to that previously described except for the provision of a means for adjustably mounting the instep pads 23' upon the inside of the shoe. This means comprises semi-tubular posts 28 mounted upon the cloth covering 24 of the pads 23'. Each of the posts 28 has an outwardly extending flange 29 provided with openings through which stitches 30 pass. The stitches 30 also pass through the cloth covering 24 of the pads. The semi-tubular posts are adapted to be passed through certain of the eyelets 13 for the purpose of adjustably positioning the pads upon the instep of the shoe.

From an inspection of Fig. 6 it will be noted that the semi-tubular posts 28 are positioned upon the pads in such a manner that the open side of adjacent posts will be directed towards each other for permitting the laces 11' to be engaged through the eyelets 13 without being limited by the posts 28.

The top ends of the portions 28 are provided with outwardly flared enlarged portions 31 which are engaged at the top faces of eyelets 13 for the purpose of retaining the posts in their engaged position with the eyelets.

In other respects this form of the invention is similar to that previously described, and like reference numerals are used for identifying like parts in each of the several views.

In Figs. 7 to 9 a modification of the invention is disclosed in which a shoe 40 is shown having a figure skate 41 mounted upon the sole thereof. The shoe 40 is formed with a narrow top 40' surrounding the foot around and above the ankle and has an open face closed by means of a lace 42 behind which a tongue 43 is located. The tongue is provided with a longitudinal slit 44 dividing the tongue into separate sections 43'. Each of the sections has its outer edge securely attached to the adjacent portion of the shoe by means of a line of stitches 45.

Inserts are mounted on the inner face of the

sections 43' of the tongue 43, and in the laced position of the shoe these inserts extend along the instep of one's foot. Each of the inserts consists of a core of rubber 46 encased with a cotton cover 47. These inserts are retained in position by means of a mucilage or adhesive material arranged between the adjacent faces of the tongue sections 43' and the cotton covers encasing the cores 46 of the inserts. When the shoe is in position on one's foot and the lace 42 is drawn tight, the adjacent edges of the sections 43' forming the tongue 43 will be caused to contact each other and seal the slit to prevent the entrance of cold air and moisture through these edges.

In other respects this form of the invention is similar to that previously described and like reference numerals are used to identify like parts in each of the several views.

In Fig. 10 a ski boot 40' is shown constructed in a manner similar to the skating shoe shown in Fig. 7.

It is to be understood that this padding arrangement may be used in connection with any type and size of shoe, such as shoes used for sportswear, military purposes, etc.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a shoe having an upper opened along its front with eyelets on either side of said opening through which a lace is to be passed for closing said opening, a pad of rubber positioned within said shoe and extended along an edge portion of said opening for protecting the adjacent area of one's foot, and means for releasably holding said pad in a desired fixed position within said shoe, said means comprising posts mounted on the ends of said pad and selectively engageable with a spaced pair of said eyelets for positioning said pad at a specific point where protection is needed.

2. In a shoe having an upper opened along its front with eyelets on either side of said opening through which a lace is to be passed for closing said opening, a pad of rubber positioned within said shoe and extended along an edge portion of said opening for protecting the adjacent area of one's foot, and means for releasably holding said pad in a desired fixed position within said shoe, said means comprising posts mounted on the ends of said pad and selectively engageable with a spaced pair of said eyelets for positioning said pad at a specific point where protection is needed, said posts being semi-circular in formation and having their open sides directed towards said opening permitting the lace to be engaged through the eyelets into which said posts are engaged.

CHARLES JEWTRAW.
